Walter L. Fry Inventor
By his Attorney,
Emery, Barth, Jauncy & Nance

UNITED STATES PATENT OFFICE.

WALTER L. FRY, OF DETROIT, MICHIGAN, ASSIGNOR, BY MESNE ASSIGNMENTS, TO
EDWARD G. BUDD MANUFACTURING COMPANY, A CORPORATION OF PENNSYLVANIA.

AUTOMOBILE BODY AND METHOD OF MAKING SAME.

1,405,680.

specification of Letters Patent. Patented Feb. 7, 1922.

Application filed February 3, 1917. Serial No. 146,323.

To all whom it may concern:

Be it known that I, WALTER L. FRY, a citizen of the United States, and a resident of the city of Detroit, county of Wayne, and State of Michigan, have invented an Improvement in Automobile Bodies and Methods of Making Same, of which the following is a specification.

My invention relates to metal automobile bodies, and more particularly to closed bodies or bodies having a standing roof, such as the well-known "Springfield type" body, and aims to provide a construction of body and method of making the same, such that the body may be constructed in the least number of operations and that in the construction of the body, the manual operations, particularly fitting and filing operations, may be avoided.

In the drawings, Fig. 1 is a side view of the rear portion of a "Springfield type" sedan body, made according to my invention; Fig. 2 is a rear view of the same body; Fig. 3 is a side view of the quarter panel of my improved body; Fig. 4 is a view of the rear panel; Fig. 5 is a sectional view of the quarter and rear panels of my improved body and Fig. 6 is a vertical sectional view of the rear panel. Figs. 7 and 8 are detail sectional views of the edge of the window opening.

It will be understood that I have illustrated a "Springfield type" body, since my invention is particularly useful in connection with this type, but that it may be applied to various other types of bodies as well.

My present invention aims to provide a construction in which the amount of welding is reduced to a minimum, and in which the parts are so arranged that when the body is assembled, any slight variation will not cause the critical positions, such as the positions of the window frames, beading etc. to be disturbed. I may thus run the beading and form the rear edge of the window opening before erecting the plates in position without fear that when erected these parts will not occupy their proper positions. I am also enabled by my invention to dispense with joints at such critical positions, so that a slight variation in the size, shape or position of the panels will cause no bad effects.

In order to obtain the results outlined above, I sub-divide the portion of my improved body lying back of the rearmost door into three sub-divisions: two quarter panels which extend from the floor line to the roof, and a rear panel which also extends from the floor line to the roof. The quarter panel shown at 1, extends from the rear edge of the door 2, to the curved portion of the body, its rear edge being shown at 3. It will be understood, however, that this panel may be made longer or shorter if desired. The rear edge 4 of the window, thus occupies a fixed relation with respect to the quarter panel, and no variation in its vertical position or the curvature of the portion 5 is possible, as in prior constructions. The upper and lower beadings 6 and 7, or any other desired ornamentation may be formed in the quarter panel by stamping, or in any suitable way, and the joint between the upper beading 6 and the half round moulding at the point *a* is eliminated.

By reason of the fact that the edge 4 of the window frame requires no hand fitting after the body has been assembled, I may roll into such portion 4, an abutment 9 for the window 10, as shown in Fig. 5, and this abutment may be formed before the quarter panel is put in place. Figs. 7 and 8 illustrate two other convenient methods of forming the window abutment. In Fig. 7 the metal sheathing is pressed into the shape shown in solid lines and then fastened to the window stile 11. It is then only necessary to bend the flange 12, inwardly into the groove in the stile, the window effectively concealing any irregularities. In Fig. 8 a wire 13, is rolled in the edge of the sheathing which by overlapping the stile forms the window abutment, as indicated.

The rear panel 14 extends from the roof to the floor line, and if desired may have a window opening 15, formed therein. The beads 6 and 7 are stamped or otherwise formed in the rear panel.

After the frame has been erected, the rear and quarter panels are applied, and welded together along the lines 16 and 17. With such a construction, the beads upon the various panels may be caused to register easily and any slight variation may be taken up on the lines 16 and 17, which do not involve

any critical positions and form relatively short welding lines upon surfaces which may be easily filed or otherwise finished.

I do not intend to confine myself to the precise structure shown and described since it is evident that many modifications may be made without departing from the spirit of my invention.

What I claim is:

10 1. In an automobile body, sheet metal quarter panels, and a sheet metal back panel, said quarter panels abutting at their rear vertical edges with and secured to the vertical edges of the back panel, each of 15 said quarter panels having a portion extending horizontally to the rear edge of the rear door of the body, and another vertical portion extending to the roof of the body, said vertical portion formed with means at its 20 forward edge to constitute a window sash abutment.

2. An automobile body having sheet metal quarter panels extending from the floor line

of the body, each panel having a horizontal portion extending forwardly towards the 25 rear door opening at the height of the arm rail, and a vertical portion extending upwardly to the body roof, said vertical portion formed at its forward vertical edge with an abutment for a window sash. 30

3. An automobile body having sheet metal quarter panels extending from the floor line to the roof of the body and conforming at their rear vertical edges to the transverse curvature of the body, each of said panels 35 having a portion thereof extending forwardly towards the rear door opening at the height of the arm rail, and the portion of said panel which extends to the roof formed at its forward vertical edge into an 40 abutment for a window sash.

In testimony whereof, I have signed my name to this specification this 30th day of January, 1917.

WALTER L. FRY.
